UNITED STATES PATENT OFFICE.

WILLIAM R. HAGER, OF CHICAGO, ILLINOIS, ASSIGNOR TO TROY LAUNDRY MACHINERY CO., LTD., OF CHICAGO, ILLINOIS, A CORPORATION OF NEW YORK.

CLOTHES-HANDLING MECHANISM.

Application filed March 4, 1920. Serial No. 363,149.

To all whom it may concern:

Be it known that I, WILLIAM R. HAGER, a citizen of the United States, residing at Chicago, in the county of Cook and State of Illinois, have invented certain new and useful Improvements in Clothes-Handling Mechanism, of which the following is a specification.

This invention relates to clothes handling mechanism.

One object of the invention is to facilitate the burdensome handling of clothes, especially when the latter are heavy.

Another object is to provide simple and efficient clothes handling mechanism which may be used as an attachment for ironing machines and the like.

These and other objects are accomplished by means of the arrangement disclosed on the accompanying sheet of drawings, in which—

Figure 1 is a perspective view of an ironing machine showing attached thereto clothes-conveying means for transferring clothes from a clothes storage means to said ironing machine;

Figure 2 is a detail view, parts being in section, showing automatically controlled locking means formed at the extensible end 30 of the clothes transfer means; and,

Figure 3 is a detail front elevation of the slotted bracket showing one link of the lazy-tongs slidably mounted therein and having a weight attachment.

The various novel features of the invention will be apparent from the following description and drawings and will be particularly pointed out in the appended claims.

The handling of clothes in laundries, especially when the clothes are heavy, is a very burdensome task and one which is extremely objectionable from the viewpoint of employees. To take a specific instance, clothes mounted over a suitable supporting bar which are transferred from any suitable clothes storage to an ironing machine, weigh, as laundries are operated, about one hundred pounds. Girls in laundries naturally object to such heavy work. Accordingly, I have provided means which greatly facilitates the handling of clothes, and particularly transferring same from clothes storage means to a clothes-treating machine.

I have chosen to illustrate my invention in connection with an ironing machine 10

having the usual conveyor 11 for passing the clothes placed thereon to rolls which iron the clothes. It is the practice to provide some suitable rack or clothes storage near the ironing machine. In this case I have shown a rack or clothes storage including four pedestals 12, 13, 14 and 15, the upper ends of pedestals 12 and 13 being connected by a transversely extending bar 16, and the upper ends of the pedestals 14 and 15 being connected by a similar transversely extending bar 17. To support the clothes on the rack bars 16 and 17, I have provided a plurality of members 18 having handles 19 and which extend between and rest upon the bars 16 and 17, said members 18 receiving and holding clothes, which, in this particular instance, may be sheets, blankets or other articles 20. It is the clothes-holding members 18 and the clothes placed thereon which are relatively heavy and which the laundry helpers object to transferring from the clothes storage means to the ironing or clothes-treating machine. To facilitate the transfer of clothes between the clothes storage means and the clothes-treating machine, I have provided transfer means, including two lazy-tongs 21 and 22, the extensible ends of which are provided with standards 23, the upper ends of which have receiving portions 24 for the clothes-holding members 18, said standards 23 being connected by a tie rod 25. The upper end of each of the two forward links 26 of the lazy-tongs is pivotally connected to its associated standard 23, the lower end of each of the other two front links 27 of the lazy-tongs having a pin 28 slidably mounted in elongated slotted portions 29 of a bracket 30 secured to the lower end of the standard 23 in each case. One rearward link 31 of each of the lazy-tongs has its upper end pivotally secured to a frame portion 32 of the ironing machine, and the other rear link 33 of each of the lazy-tongs is provided with a pin 34 which is slidably mounted in elongated grooves 35 in a bracket 36 forming a part of or supported by the frame of the ironing machine. It will be appreciated that it is necessary to provide for some vertical movement of the links of the lazy-tongs when said lazy-tongs are extended and retracted. For this reason the slotted brackets 30 and 36 are provided. It will be noted that the lazy-tongs extending between the ironing 110

machine and the clothes rack incline slightly upwardly from the ironing machine toward the clothes rack, the object being to cause the lazy-tongs automatically to retract or travel from the clothes rack to the ironing machine without any external force being applied thereto. The lazy-tongs automatically, when unloaded, will retract as above mentioned. To facilitate this movement, however, I have provided weights 36 which are connected to the cross pins 33 and which pull downwardly upon the links 32, such action naturally being to retract the lazy-tongs. When the clothes-holding member 18 and clothes carried thereby are mounted upon the carrier or lazy-tongs, the weight of the former increases the tendency of the lazy-tongs to retract. By means of this arrangement the heavy clothes may be transferred from the clothes rack or storage means to the ironing machine in a simple and efficient manner and with very little effort.

When the lazy-tongs are extended, as shown in Figure 1 of the drawings, the hooked ends 37 of locking dogs 38 automatically pass over and engage cooperating locking members or bars 39 carried by the transversely extending bars 16 and 17, it being understood that the locking dog 29 in each case is pivotally mounted at 40 to the upper end of the standards 23 or the supporting members 24 carried thereby. It is apparent, therefore, that when the lazy-tongs are extended and no clothes-holding member is mounted on the standards 23, the locking dogs 38 will engage the locking members 39 for holding the lazy-tongs or the carrier in extended position, it being understood that the weight of the hooked portions 37 of the dogs 38 is sufficient to cause the hooked ends of the dogs to move downwardly under the influence of gravity. However, the locking dogs 38 are automatically unlocked to release the carrier or lazy-tongs when the clothes-holding member 18 is slid from the supporting bars 16 and 17 onto the supporting standards 23 of the carrier, the clothes-holding members 18 passing over the dogs 38 and engaging the then up-standing ends 41 of the locking dogs 38 and depressing same to release the dogs and accordingly the clothes carrier. As mentioned hereinabove, when this happens the lazy-tongs automatically retract and transfer the clothes from the rack to the ironing or other clothes-treating machine.

It is my intention to cover all modifications of the invention without departing from the spirit and scope of the following claims.

I claim:

1. In clothes-handling mechanism for transferring clothes, the combination of a clothes storage means, means for transferring clothes from a point adjacent to said

storage means to a point displaced therefrom, means for locking said transferring means to said storage means whereby clothes may be moved directly from the storage means onto the transferring means, and means for automatically releasing said transferring means placed in position to be operated in such direct movement.

2. In clothes-handling mechanism for transferring clothes, the combination of clothes storage means, a carrier for moving clothes from said clothes storage means to a point displaced therefrom and locking means associated with said carrier and storage means whereby the carrier may be locked to said storage means, means for automatically unlocking said locking means in the normal operation of moving clothes from said clothes storage means to said carrier.

3. In clothes-handling mechanism for transferring clothes, the combination of clothes storage means, a carrier for moving clothes from said clothes storage means to a point displaced therefrom, locking means associated with said carrier and storage means whereby the carrier may be locked to said storage means, and means for automatically releasing said carrier in the normal operation of moving clothes from said clothes storage means to said carrier.

4. In clothes-handling mechanism, the combination of the frame of a clothes-treating machine, clothes storage means, and lazy-tongs mechanism extending therebetween for transferring clothes from one to the other, said lazy-tongs being biased to a position adjacent to said clothes treating-machine frame.

5. In clothes-handling mechanism, the combination of a clothes-treating machine frame, clothes storage means, lazy-tongs mechanism extending therebetween for transferring clothes from one to the other, and means connected to said lazy-tongs mechanism for biasing same in one direction.

6. In clothes-handling mechanism, the combination of a clothes-treating machine frame, clothes storage means, lazy-tongs mechanism extending therebetween for transferring clothes from one to the other, and means connected to said lazy-tongs mechanism for biasing said lazy-tongs mechanism to a position in proximity with said clothes-treating machine frame, and means responsive to the normal operation of transferring clothes from said clothes storage means to said lazy-tongs for controlling the operation of said lazy-tongs.

7. In clothes-handling mechanism, the combination of a clothes-treating machine frame, clothes storage means, lazy-tongs mechanism for transferring clothes between

said clothes-treating machine frame and clothes storage means, and a weight operatively connected to a link of said lazy-tongs mechanism for biasing same to a position adjacent to said clothes-treating machine frame.

8. In clothes-handling mechanism, the combination of a clothes-treating machine frame, clothes storage means, a carrier for carrying clothes from one to the other, and an automatically actuated locking member carried by said carrier and arranged to lock same to said clothes storage means.

9. In clothes-handling mechanism, the combination of a clothes-treating machine frame, clothes storage means, a carrier for carrying clothes from one to the other, an automatically actuated locking member carried by said carrier and arranged to lock same to said clothes storage means, and clothes-holding means adapted to be manually moved from said clothes storage means to said carrier, said locking member being adapted to be released automatically in the normal operation of moving said holding means to said carrier.

10. In clothes-handling mechanism, the combination of a clothes-treating machine frame, clothes storage means, a carrier for carrying clothes from one to the other, an automatically-actuated locking member carried by said carrier and arranged to lock same to said clothes storage means, clothes-holding means adapted to be moved from said clothes storage means to said carrier, said locking member being adapted to be released automatically in the normal operation of moving said holding means to said carrier, and means operatively connected to the carrier for biasing said carrier to transfer the clothes from the clothes storage means to said clothes-treating machine frame.

11. An attachment for a clothes-treating

machine comprising lazy-tongs mechanism 45 whereby clothes may be conveyed with respect to said machine during an operative movement of said lazy-tongs, and means operatively connected to a link of the lazy-tongs for biasing said lazy-tongs to retracted position.

12. An attachment for a clothes-treating machine comprising lazy-tongs mechanism whereby clothes may be conveyed with respect to said machine during an operative 55 movement of said lazy-tongs, latching means for holding said lazy-tongs in unretracted position, clothes-holding means, said latching means being provided with unlatching means responsive to said clothes-holding 60 means.

13. An attachment for a clothes-treating machine comprising lazy-tongs mechanism whereby clothes may be conveyed with respect to said machine during an operative 65 movement of said lazy-tongs, means operatively connected to a link of said lazy-tongs for biasing said lazy-tongs to retracted position, latching means for holding said lazy-tongs in unretracted position, clothes-holding 70 means, and unlatching means for said latching means responsive to said clothes-holding means.

14. In combination, clothes storage means, a clothes-treating machine frame, a carrier 75 between said storage means and said treating machine frame biased to move to a position adjacent to said treating machine frame, said carrier being provided with latching means for holding same in proximity to said storage means, clothes-holding means, and unlatching means responsive to said clothes-holding means for unlatching said latching means.

Signed at Chicago, Illinois, this 28th day 85 of February, 1920.

WILLIAM R. HAGER.
